SOAP DISH HOLDER

Raymond U. H. Tegner, Lodi, Wis. (% Amerock Corporation, 4000 Auburn St., Rockford, Ill. 61101)

Original design application Jan. 10, 1972, Ser. No. 216,892. Divided and this application Mar. 19, 1973, Ser. No. 346,405

Term of patent 14 years

Int. Cl. D6—06

U.S. Cl. D6—90

FIG. 1

FIG. 2

FIG. 3

FIG. 4

FIG. 1 is a side view of a soap dish holder incorporating my new design.

FIG. 2 is a top view of a soap dish holder.

FIG. 3 is a front elevational of the soap dish holder as seen from the left in FIG. 1.

FIG. 4 is a sectional view taken along the line 4—4 in FIG. 3.

This application is a division of my co-pending application Ser. No. 216,892, filed Jan. 10, 1972.

I claim:

The ornamental design of a soap dish holder, as shown.
